CRANKSHAFT GRINDER

Mervin Stiles, Spokane, Wash.

Application November 7, 1952, Serial No. 319,268

2 Claims. (Cl. 51—241)

1

This invention relates to crankshaft grinders and particularly to those of the type used for regrinding the throws of an engine crankshaft while the crankshaft is located in the engine block.

One object of the invention lies in the provision of a crankshaft grinder which may be used in a wide variety of engines, particularly diesel engines of the V-type, without requiring removal of the crankshaft from the block.

Another object of the invention lies in the provision of a crankshaft grinder which may be readily adapted to grind the crankshaft throws without requiring removal of the engine block from the vehicle.

Another object of the invention lies in the provision of a crankshaft grinder which may be supported from a portion of the throw to be ground, and thus will require a limited amount of space to perform the grinding operation.

Another object of the invention lies in the provision of a crankshaft grinder in which accurate positioning of the grinding wheel face with respect to the crank throw may be obtained more easily and with less expense.

Another object of the invention lies in the provision of a spring biased grinding face which will permit the grinding wheel to traverse a path commensurate with the circumferential face of the throw and preclude undue pressure from being exerted upon the grinding wheel.

These and other objects of the invention will become apparent during the course of the following description.

In diesel motors of the V-type present in some railroad locomotives, it is common to find two connecting rods bearinged on the same throw in side by side relation. This specification will be primarily concerned with regrinding this type of crankshaft. However, it is not my intention to limit my invention to this one application only, since it is conceivable that the invention may be applied to other crankshafts as long as the physical sizes of the component parts are reduced to comply with the longitudinal dimension of the throw to be resurfaced or ground.

In the accompanying drawings, forming a part of this specification, and in which like numerals are employed to designate like parts,

Figure 1 is a fragmentary side elevation of a crankshaft showing the crankshaft grinder in position on a crank throw;

Figure 2 is a partial transverse sectional view upon an enlarged scale of a crankshaft throw and the crankshaft grinder as at line 2—2 of Figure 1;

Figure 3 is a transverse sectional view upon a further enlarged scale and taken through the grinding wheel and its supporting head as at line 3—3 of Figure 1;

Figure 4 is a longitudinal vertical cross section taken through the tool mounting plate and the associated ways as at line 4—4 of Figure 2;

Figure 5 is a plan view partially in horizontal cross section as at line 5—5 of Figure 2; and

Figure 6 is a fragmentary perspective view of the connecting rod and cap which constitute a collar adapted to support my improved crankshaft grinder.

Referring now to Figure 6, there is shown a connecting rod 10 which has the usual segment of a bearing 11 at its lower end, and it will be understood that the upper end is united with a piston located in a cylinder as is common to internal combustion engines. To secure the connecting rod about a throw, a cap 12 is applied thereto by means of bolts 13 which extend upwardly through the cap and are threadedly engaged in the connecting rod 10. The connecting rod 10 together with the cap 12 encircles the throw 14. A portion of the connecting rod cap 12 is routed out as at 15 and provides a tool receiving slot which has a mounting face 16 and spaced parallel walls 17 on either side of the face 16 and at right angles thereto. The slot 15 is disposed radially from the throw when the cap 12 is secured to connecting rod 10 in encircling relation to the throw 14. A positioning groove 18 is formed in the face 16 midway the width thereof and radially extending and is adapted to receive the rib 19 which is formed on the back face of the tool mounting plate 20. Tool mounting plate 20 is provided with a plurality of bolt receiving holes 21 which are adapted to register with the threaded apertures 22 formed in the face 16 and which receive cap bolts 23 to secure mounting plate 20 in face to face engagement with face 16.

Since it is required that the movement of the grinding head be parallel with the axis of throw 14, it becomes necessary to supply means of adjusting the vertical tilt of plate 20. Therefore, I have supplied spaced set bolts 24 midway the width of plate 20 and spaced one above the other to bear against the bottom face of positioning groove 18. The tilt of plate 20 may thus be adjusted by loosening bolts 23 and threading the set bolts 24 selectively through plate 20 and thence again tightening bolts 23. Plate 20 is provided with opposed rails 25 which are V-shaped in cross section and extend vertically along the

side edge faces of the plate spaced from the rear face thereof. The grinding head 26 is supported on spaced ways 27 which are disposed in parallel relation to the axis of throw 14 and are adjustably spaced therefrom by means of a supporting wall 28. The wall 28 is provided with opposed V-shaped grooves 29 and 30 which are adapted to slide over rails 25 longitudinally of plate 20. A means of eliminating play between the plate 20 and wall 28 is provided at 31 and is common in the art.

As shown in Figures 2 and 3, ways 27 have planar top 32, bottom 33 and side faces 34 and 35. The inner side faces 34 and the top and bottom faces 32 and 33 are finished to provide a smooth surface upon which head 26 may be supported for reciprocating movement longitudinally of the ways 27. The mounting plate 20 is provided with an ear 36 which has a vertically disposed internally threaded aperture 37 therein, and the supporting wall 28 is provided at its lower edge midway the width thereof with an ear 38 having a bore 39 aligned with the aperture 37 of ear 36. An adjusting bolt 40 is rotatably carried in the ear 38 and secured therein by means of a washer 41 and the threaded end of the bolt 40 is threadedly engaged in the aperture 37. Rotation of the bolt 40 will, therefore, shift the ways 27 vertically to selective adjusted positions relative to the throw 14.

With reference to Figure 3, it will be seen that head 26 is provided with a body 42 having opposed slots 43 which are slidably engaged over the ways 27 to permit longitudinal movement of the head 26 along the ways 27. The body 42 is provided with a bore 44 which is aligned radially with the throw 14 and has an enlarged portion or well 45 at its upper end and a recess 46 at its lower end. A sleeve bushing 47 is disposed in the bore 44 and is provided at its upper end with an external flange 48 and at its lower end is threadedly engaged in a nut 49 which limits upward movement of the bushing. An expansion spring 50 is positioned in the well 45 and urges the sleeve bushing 47 upwardly by providing expanding pressure between flange 48 and the body 42. Thus it will be seen that sleeve bushing 47 is longitudinally shiftable in bore 44 and is biased upwardly by expansion spring 50. A grinding wheel shaft 51 extends through sleeve bushing 47 and has an integral dust or grinding protector 52 at the upper end of sleeve bushing 47, and a similar protector 52' is secured on the shaft 51 adjacent its lower end by means of nut 53 threaded thereon. The upper end of shaft 51 is provided with an axial bore 54 terminating in a reduced internally threaded socket 55 which is adapted to receive a bolt 56 provided to secure cup-shaped grinding wheel 57 to the shaft 51. The grinding wheel 57 is provided with a grinding face 58 at its upper end which is positioned tangent to the surface of the throw 14. Suitable lubricating and packing means are applied to the head to provide proper lubrication and exclude the abrasive materials used in grinding from getting into the working parts of the tool.

As seen in Figure 1, the connecting rod 10 is confined on the throw bearing 14 by means of a spacing wheel 59 which is carried by the connecting rod cap 12 on a side face thereof and is adapted to bear against one of the spaced crank arms 60 carried by main bearings 61. It will thus be seen that the connecting rod 10 and its cooperating cap 12 provide a collar which is adapted to consume not more than one-half

of the longitudinal dimension of the throw bearing which is to be ground. It is obvious that the cap, and therefore the grinding tool, may be reversed to grind the opposed portion of the throw, and also any means of rotary power (not shown) may be applied to the grinding wheel whether it be supported by the head 26 or supplied through a flexible cable 62 as shown in Figure 1.

Referring to Figures 2 and 6, it will be seen that packing 63 is provided in a groove formed about the marginal edges of bearing segment 11 and cap 12 where they meet with throw bearing 14, thus eliminating abrasive particles from entering the bearing of connecting rod 10.

It will be noted in Figures 1 and 3 that clamping bands 64 may be applied to one or both of the ways 27 to limit the longitudinal movement of head 26. Thus when an operator shifts the head by means of handle 65 pivotally secured to yoke 66 carried by the body 42, his movement may be restricted within the confines of the clamping bands 64. If the throw 14 is out of round, the high point will exert greater pressure upon the grinding face 58 of grinding wheel 57 and spring 50 will compress, permitting shifting of the grinding wheel 57 and thus preventing breakage thereof.

Having thus described my invention, I claim:

1. A power tool for grinding the throws of an engine crankshaft while positioned in the engine comprising a connecting rod rotatably carried by said throw and confined to consume not more than one-half of its longitudinal dimension, a connecting rod cap removably secured to said rod and together with said rod encircling said throw, a tool mounting plate on said cap, spaced ways slidably mounted on said tool mounting plate and disposed in selective spaced parallel relation to said throw, an adjusting screw threadedly associating said ways and mounting plate for selective movement of said ways relative to said throw, and a head having a powered grinding wheel rotatably supported thereby and disposed with its grinding face tangent to the surface of said throw, said head being supported for longitudinal movement along the ways and parallel with the axis of said throw.

2. The invention as defined in claim 1 wherein the head comprises a body having opposed recesses slidably engaging said ways, said head being provided with a bore having its axis disposed radially from said throw, a bushing sleeve slidably in said bore and having a flange on its upper end, a well about the upper end of said bore, an expansion spring disposed in said well and urging said flange upwardly, means on the lower end of said bushing limiting the upward movement thereof, and a grinding wheel shaft rotatably carried by said bushing and uniting said grinding wheel with its power source.

MERVIN STILES.
